(57) **CLAIM**

The ornamental design for a landscape edging, as shown and described.

DESCRIPTION

FIG. 1 is a front isometric view of a landscape edging showing our new design;

FIG. 2 is a front elevation view thereof, the rear elevation view being identical thereto;

FIG. 3 is a right-side elevation view thereof, the left side elevation view being identical thereto;

FIG. 4 is a top plan view thereof;

FIG. 5 is a bottom plan view thereof; and,

FIG. 6 is a top plan view thereof, showing the landscape edging of FIG. 1 in an alternate configuration.

The landscape edging is shown with a symbolic break in its length. The appearance of any portion of the landscape edging between the break lines forms no part of the claimed design. The broken lines immediately adjacent to the shaded areas represent portions of the landscape edging that form no part of the claimed design.

1 Claim, 4 Drawing Sheets
